ADVERTISING VEHICLE

Wendell R. Ninabuck, Milwaukee, Wis.

Application March 10, 1955, Serial No. 34,985

Term of patent 14 years

(Cl. D14—3)

Fig. 1

Fig. 2

Fig. 3

Fig. 4

I claim:

The ornamental design for an advertising vehicle, as shown.
